COMBINED PACKAGING AND DISPLAY BOX FOR WATCHES OR THE LIKE

Francis E. Blod, Tuckahoe, N. Y., assignor to The Farrington Manufacturing Company, Boston, Mass., a corporation of Massachusetts

Application August 19, 1954, Serial No. 31,918

Term of patent 14 years

(Cl. D80—5)

FIG. 1

To all whom it may concern:

Be it known that I, Francis E. Blod, a citizen of the United States, residing at Tuckahoe, in the county of Westchester and State of New York, have invented a new, original, and ornamental Design for a Combined Packaging and Display Box for Watches or the like, of which the following is a specification, reference being had to the accompanying drawing, forming a part hereof, wherein

Fig. 1 is a front perspective view of a combined packaging and display box for watches or the like showing my new design;

Fig. 2 is a top plan view;

Fig. 3 is a front elevational view; and
Fig. 4 is an end elevational view thereof.

I claim:

The ornamental design for a combined packaging and display box for watches or the like, as shown.
